Primary Examiner—M. N. Pandozzi**Attorney, Agent, or Firm**—Brinks Hofer Gilson & Lione**[57]****CLAIM**

The ornamental design for a serving tray, as shown and described.

DESCRIPTION

FIG. 1 is a top perspective view of a serving tray showing my new design;

FIG. 2 is a top plan view thereof;

FIG. 3 is a sectional view taken along line 3—3 of FIG. 2;

FIG. 4 is a sectional view taken along line 4—4 of FIG. 2;

FIG. 5 is a sectional view taken along line 5—5 of FIG. 2;

FIG. 6 is a sectional view taken along line 6—6 of FIG. 2;

FIG. 7 is a sectional view taken along line 7—7 of FIG. 2;

FIG. 8 is a left side elevational view thereof;

FIG. 9 is a right side elevational view thereof;

FIG. 10 is a front elevational view thereof;

FIG. 11 is a rear elevational view thereof; and,

FIG. 12 is a bottom plan view thereof.

The broken line showing of a bow and hat portion in FIG. 1 is for illustrative purposes only and forms no part of the claimed design.
